DESIGN FOR A KNIFE SHARPENER

Rudolph Boettinger, Englewood, N. J.

Application January 5, 1945, Serial No. 117,276

Term of patent 14 years

(Cl. D37—1)

To all whom it may concern:

Be it known that I, Rudolph Boettinger, a citizen of the United States, residing at Englewood, in the county of Bergen and State of New Jersey, have invented a new, original, and ornamental Design for a Knife Sharpener, of which the following is a specification, reference being had to the drawing forming a part thereof.

In the drawing:

Fig. 1 is a perspective view of a knife sharpener showing my new design;

Fig. 2 is a side elevational view thereof;

Fig. 3 is a top plan view thereof; and

Fig. 4 is a bottom plan view thereof.

I claim:

The ornamental design for a knife sharpener, substantially as shown.

RUDOLPH BOETTINGER.
